(57) **CLAIM**

The ornamental design for a luminaire unit assembly, as shown and described.

DESCRIPTION

FIG. 1 is a top plan view of a luminaire unit assembly according to a first embodiment of the invention;

FIG. 2 is a perspective view of a luminaire unit assembly illustrated in FIG. 1;

FIG. 3 is a front elevation view of a luminaire unit assembly illustrated in FIGS. 1 and 2;

FIG. 4 is a right elevation view of a luminaire unit assembly illustrated in FIGS. 1-3;

FIG. 5 is a bottom plan view of a luminaire unit assembly illustrated in FIGS. 1-4;

FIG. 6 is a perspective view of a luminaire unit assembly illustrated in FIGS. 1-5;

FIG. 7 is a top plan view of a luminaire unit assembly according to a second embodiment of the invention;

FIG. 8 is a perspective view of a luminaire unit assembly illustrated in FIG. 7;

FIG. 9 is a front elevation view of a luminaire unit assembly illustrated in FIGS. 7 and 8;

FIG. 10 is a right elevation view of a luminaire unit assembly illustrated in FIGS. 7-9; and,

FIG. 11 is a bottom view of a luminaire unit assembly illustrated in FIGS. 7-10.

The luminaire unit assembly claimed herein is an article with multiple independent parts that interact with each other. Any broken line illustration of environmental structure in the drawings is not part of the design sought to be patented; however, the distances and relative proportions among the claimed portions separated by broken lines is part of the design.
